UNITED STATES PATENT OFFICE.

JAMES L. AUBLE, OF TOLEDO, OHIO, ASSIGNOR, BY DIRECT AND MESNE ASSIGNMENTS, OF ONE-HALF TO NANCY M. AUBLE AND ONE-HALF TO JEANNETTE M. SEYBOLD, OF TOLEDO, OHIO.

METAL-REFORMING METHOD AND APPARATUS.

Application filed February 11, 1924, Serial No. 691,965. Renewed October 1, 1928.

This invention relates to the production of shapes especially in arc lengths.

This invention has utility when incorporated for handling straps or strips of sheet metal for making rings thereof in special configuration in cross section, as in the production of demountable rims for motor vehicle tires.

Referring to the drawings:

10 Figure 1 is a side elevation of an embodiment of the invention in a tire rim forming machine;

Fig. 2 is a perspective view of a strip of material showing the stages of reforming;

15 Fig. 3 is a plan view of the machine of Fig. 1;

Fig. 4 is an elevation of the machine from the left of Fig. 3;

20 Fig. 5 is a section on the line V—V Fig. 3;

Fig. 6 is a partial section on the line VI—VI Fig. 3;

Fig. 7 is a partial section on the line VII—VII Fig. 3; and

25 Fig. 8 is a section through the die on the line VIII—VIII Fig. 3.

Upon main base 1 is mounted motor 2 having shaft 3 carrying sprocket 4 about which extends sprocket chain 5 to sprocket wheel 6 on shaft 7. This shaft 7 is carried by frame members 8, 9. Pinion 10 on this shaft 7 is effective to drive gear 11 on shaft 12 extending through frame members 8, 9, 13 and 14. These frame members 8, 9, 13, 14 are fixed to the main base 1 by bolts 15, and are further braced as to each other by tie members 16, anchored by bolts 17. On this shaft 12 between the members 8, 9, is gear 18 in mesh with gear 19 therebelow on shaft 20 extending parallel to the shaft 12 and through the main frame members 8, 9, 13, 14.

40 Primary guide and push roll 21, fast on the shaft 12 has its flanges 22 overlap opposing roll 23 on the shaft 20. These rolls 21, 23, form an initial or primary pair of rolls for receiving strip sheet metal stock. Each of these rolls 21, 23, is power driven, and the stock is forced from this pair of rolls of the roll forming train to the next succeeding pair of rolls.

45 Mounted on the shaft 12 on the opposite side of the machine from the gear 11 is gear 24, in mesh with gear 25 on shaft 26, carried by the frames 8, 9, 13, 14. This shaft

26 has pinion 19 thereon in mesh with pinion 18 on shaft 27. The shaft 27 carries roll 28, 55 opposing companion roll 29 on the shaft 26. These rolls 28, 29, form the second pair of the roll train and initiate the transverse flange for reforming of the strip material.

50 Mounted on the shaft 27 is gear 30 in mesh with gear 31 on shaft 32, extending through the frame 8, 9, 13, 14. This shaft 32 between the frame members 8, 9, has pinion 19 in mesh with pinion 18 on shaft 33, parallel to shaft 32. This shaft 33 carries reforming roll 34, opposing companion roll 35 on the shaft 32, as the third pair of reforming rolls in this rolling train. This third pair increases the degree of transverse reforming, and as shown has reduced the overall width 60 of the strip material by so doing. The shaft 33 on the side of the frame carrying the gear 24 is provided with gear 36, in mesh with gear 37, on the shaft 38, extending through the frame members 8, 9, 13, 14. This shaft 38 has thereon pinion 19, between the frame members 8, 9, in mesh with pinion 18 on the shaft 39, parallel to the shaft 38. On this shaft 39 is reforming roll 40, opposing companion roll 41. These reforming rolls 40, 41, 65 provide the terminal pair of reforming rolls in this train and still further reduce the overall width of the strip material by increasing the flange thereof.

70 The frame portions 8, 9, 13, 14, carry adjustable bearings 42, for these roller bearing shafts, so that the positions between the roll pairs may be nicely adjusted to take care of the thickness of stock being operated upon. This degree of proximity of the rolls is such 75 that there is not only a firm holding of the sheet stock but in the forcing or propelling of the stock through this train of rollers there is incidental to the reworking of the material a building up of temperature there- 80 in to quite a degree, even with stock starting cold, or normal temperature, as fed in the machine. This building up of the temperature in the stock makes it more susceptible 85 for the extreme reforming in the latter stage.

90 Pivot mounting 42' for die sections 43, 44, is so disposed that advance or entrance portion 45 of these die sections 43, 44, are in close proximity to the stock as leaving the region of reforming between the terminal 95 pair of reworking rolls 40, 41. This hot

stock as forced from this final roll pair 40, 41, is thrust into these entrance portions 45 of the dies 43, 44. These dies 43, 44, in extending from this final roll pair, 40, 41, still further crowd in or diminish the maximum overall size of the stock, to effect an overhanging bending back or beading of the flanged stock as passing from the final roll pair. In normal rolling between a roll pair this overhanging beading would not be possible, as the opposing rolls could not clear the material and effect such shaping. However, herein the forcing action of the roll train is effective to propel this reworked material for further working into and through the die pair 43, 44. The die pair 43, 44, may be adjusted to take up transverse wear by bolts 46.

It is further noted that this die pair 43, 44, as beyond the final roll pair has its curvature perpendicular to the axis of the shafts of the final roll pair, which makes these dies effective not only for narrowing the stock in giving the edges an overhang but for bending the straight strip stock into a ring form.

This die pair is adjustable by bolt 47 in bracket 48, to rock in its pivot mounting 42', for proper adjustment of the arc control in producing, say demountable rims 49, from strips of stock which may be cut to the desired length and thrust successively into the machine for feeding therethrough and automatic discharge therefrom, as twisted slightly to one side by bracket 50, for clearing the machine in making the complete circle or arc form.

In practice under the invention herein disclosed there may be completed in a single operation transverse and longitudinal reforming even to the degree of desired overhanging in the transverse reforming. A production return on this machine is possible for large output and low material and labor costs. When operating the machine for the production of rims, quite a wide range of forms may be made by changing the die 43, 44, and using the same train of pairs of rolls.

What is claimed and it is desired to secure by Letters Patent is:

50 1. Re-forming strip metal stock embodying transversely re-shaping said stock by rolling in a plane, and in addition to said rolling and as a continuation therefrom increasing the degree of the transverse re-shaping by causing said rolling re-shaping to propel the stock therefrom through a stationary die out of said plane.

60 2. Re-forming straight strip metal stock embodying transversely re-shaping said stock by rolling, causing said rolling to propel the stock therefrom through a stationary die for increasing the degree of the transverse re-shaping, and simultaneously causing said stock to be re-shaped longitudinally to pro-

vide a channel open in the plane of the longitudinal re-shaping.

3. Flanging straight strips continuously throughout their length and forming the same into rings as a continuous progressive process embodying rolling parallel flanges in spaced relation along said strips, and simultaneously re-forming longitudinally to provide a channel open in the plane of the longitudinal re-forming, and further re-forming transversely by causing said rolling to propel the strips through a stationary die in reducing the spacing between the straight edges of the flanges to less than the spaced relation of said flanges where they rise from the strip.

4. A metal re-working machine embodying a succession of rolls providing a line of travel for material as reworked for marginally flanging, a closing die of longitudinal arc imparting form for inwardly bending the free edges of the marginal flanging of the material as the material is longitudinally curved to ring form, and driving means for the rolls for propelling material therefrom through said die.

5. A metal re-working machine embodying a train of roll pairs, driving means therefor, therefrom a further re-shaping embracing stationary die pair of forming members for receiving material and acting thereupon as forced thereinto by said roll pairs, means providing a pivotal mounting for the die on an axis parallel to the axis of the roll pairs, and adjusting means parallel to the stationary die pair axis for varying the spacing between the stationary die pair forming members.

6. A metal re-working machine embodying a train of roll pairs including a terminal roll pair, therefrom a further re-shaping embracing adjustable width stationary die of arc form mounted to extend into proximity to the re-forming region of the terminal roll pair, and driving means for the roll pairs for progressing material from said terminal roll pair into and through said die, the axis of the die arc being transversely of the line of the roll pairs.

7. A metal re-working machine embodying a pair of rolls, an embracing die comprising a pair of relatively adjustable right and left members, said die being of arc form, having its axis parallel to the axis of the rolls and extending between said rolls into the region adjacent the re-working coaction of said rolls, a fixed pivotal mounting for the die, means for adjusting the die on said mounting, and driving means for said rolls for propelling material therefrom directly into and through the arc form of said die.

In witness whereof I affix my signature.

JAMES L. AUBLE
